CLAIM

The ornamental design for a sensor device, as shown and described.

DESCRIPTION

FIG. 1 is a front view of a sensor device showing our new design.

FIG. 2 is a rear view thereof.

FIG. 3 is a left side view thereof.

FIG. 4 is a right side view thereof.

FIG. 5 is a top view thereof.

FIG. 6 is a bottom view thereof.

FIG. 7 is a top-right-front perspective view thereof.

FIG. 8 is a bottom-right-rear perspective view thereof.

FIG. 9 is a top-left-rear perspective view thereof; and,

FIG. 10 is a bottom-right-front perspective view thereof. The broken line showing of a logo on a sensor device is for the purpose of illustrating environmental structure, and forms no part of the claimed design.

The broken lines in FIGS. 2, 8, and 9 show portions of a sensor device that form no part of the claimed design.

The shade lines show surface contour and not surface ornamentation.
